[57] CLAIM

The ornamental design for a combined set of markers
and holder therefor, as shown and described.

DESCRIPTION

FIG. 1 is a top perspective view of a combined set of
markers and holder therefor showing my new design;
FIG. 2 is a front elevational view;

FIG. 3 is a rear elevational view;

FIG. 4 is a left side elevational view, the right side being
a mirror image thereof;

FIG. 5 is a top plan view; and,

FIG. 6 is a bottom plan view thereof.

FIG. 1

FIG. 2

FIG. 3

FIG. 4

FIG. 5

FIG. 6
